UNITED STATES PATENT OFFICE.

FRED FOX AND SIMON E. LOTZ, OF LIMA, OHIO.

PORCH-SWING.

1,260,358.

Specification of Letters Patent. Patented Mar. 26, 1918.

Application filed July 12, 1916. Serial No. 108,867.

To all whom it may concern:

Be it known that we, FRED FOX and SIMON E. Lorz, citizens of the United States, residing at Lima, in the county of Allen, State of Ohio, have invented certain new and useful Improvements in Porch-Swings; and we do hereby declare the following to be a full, clear, and exact description of the invention, such as will enable others skilled in the art to which it appertains to make and use the same.

This invention relates to porch swings and has special reference to a folding chair for swings of this description.

15 The principal object of the invention is to improve and simplify the general construction of devices of this character.

The second important object of the invention is to provide a porch swing of this character wherein the same devices which serve to hold the arms of the swing in erect position relative to the seat will likewise support the seat when the proper chains or ropes are attached thereto.

25 A third important object of the invention is to provide a porch swing so arranged and constructed in an improved manner that the side members of the swing will fold flat upon the top of the seat while the back 30 member of the swing will fold flat underneath the seat.

With the above and other objects in view, such as will be hereinafter apparent the invention consists in general of certain novel 35 details of construction and combinations of parts hereinafter fully described, illustrated in the accompanying drawings, and specifically claimed.

In the accompanying drawings, like characters of reference indicate like parts in the 40 several views, and:

Figure 1 is a front view of the swing in erect position.

Fig. 2 is a side view thereof.

45 Fig. 3 is a perspective view of the swing folded.

Fig. 4 is a section on the line 4—4 of Fig. 2.

Fig. 5 is a section similar to Fig. 4, showing the parts folded.

Fig. 6 is a section on the line 6—6 of Fig. 2.

In carrying out the objects of the invention in the present embodiment thereof 55 there is provided a bottom or seat which

consists of side members 10 and a front member 11. These side members serve to support slats 12, the slats being rabbeted into the side members.

Each of the sides consists of a lower member 13 and an upper member 14, these members being connected at the front by a front post 15 and at the rear by a diagonal rear post 16. Vertical slats 17 are also interposed between the members 13 and 14. 60

Connecting the members 10 and 13 are hinges 18 which are so arranged that their pintles are at the inner edges of said members 10 and 13 so that the sides can be folded flat on the seat or can be erected in such 65 manner that the member 13 on each side will rest on the member 10. In order to hold these sides in erected position suitable openings are provided in the members 10, 13 and 14 and through these openings pass eye bolts 70 19 having eyes 20 at their upper ends and nuts 21 at their lower ends. It will be noted that when these eye bolts are in position with the nuts screwed on the sides can not be bent down to lie on the seat and that the 75 eyes in the upper ends of these bolts serve as clutching means for the supporting chains or ropes so that the weight is supported on the bottom and not at all on the sides. 80

The rear ends of each of the members 10 are beveled as at 21' and hinged beneath these beveled ends are the beveled end members 22 of the back, these end members being connected by top and bottom members 23 90 between which extend slats 24. The end members 22 fit between extensions 25 formed on the rear ends of the members 14 and when in position between these extensions bolts 26 are passed through said members 22 and the 95 extensions 25 to hold the back upright. Moreover, by the construction herein set forth the back is enabled to lie flat against the bottom of the seat as shown in Fig. 3.

There has thus been provided a device 100 which can be readily set up for use and which can be folded together for transportation or storage, into a very small and compact bundle so that it occupies but very little space. 105

It is obvious that many minor changes may be made in the form and construction of the invention without departing from the material principles thereof. It is not therefore desired to confine the invention to the 110

exact form herein shown and described but it is wished to include all such as properly come within the scope claimed.

Having thus described the invention, what is claimed as new, is:—

- 5 1. A folding swing including a seat, a back hinged to the seat and movable to interchangeably fold thereunder and stand thereon, arms hinged to the seat and movable to interchangeably fold thereon and stand thereupon, said arms having sockets at their ends disposed to receive the back when the arms and back are standing upon the seat, said arms having also fingers disposed to overlap the ends of the back when the arms and back are standing upon the seat, and bolts removably engaged through the fingers and the overlapping portions of the back.
- 10 2. A folding swing comprising a seat member having perforations in its end portions, arms hinged to the seat for movement to interchangeably lie and stand thereupon, each arm including top and bottom members having registering perforations

disposed to register respectively with the perforations of the seat when the arms are standing thereon, a bolt removably engaged through each series of registering perforations to hold the arms in erect position and 30 adapted at their upper ends for attachment of suspending means, whereby they may be held against lateral bending under the influence of inward folding tendency of the arms, the top members of the arms having 35 end sockets and resultant fingers, and a back hinged to the seat and movable to interchangeably lie against the bottom of the seat and to stand thereupon in engagement with the socket and against the fingers, and bolts 40 removably engaged through the fingers and the corresponding portions of the back.

In testimony whereof we affix our signatures in the presence of two witnesses.

FRED FOX.
SIMON E. LOTZ.
